which is disposed between orifices 40 and 42 and perpendicular thereto. Rotatably mounted on shaft 60 are a pair of oppositely extending wing-like valve closure members 62 and 64. Each closure member 62 and 64, in turn, is provided with a circular rubber-like disk 66 and 68 which is adapted for abutting engagement with the open end of its associated orifice 40 and 42. Closure members 62 and 64 are normally biased clockwise and counterclockwise, respectively, by means of a double ended coil torsion spring 70, the opposite ends of which engage the bottom walls 72 and 74 of the respective closure members. Disposed in the hollow neck 52 of valve housing 50 in axial alignment with stub shaft 60 is a valve operating shaft 76. At its outer end 78, shaft 76 is conical in cross section and has an axial bore 80 formed therein which is adapted to receive the outer end of stub shaft 60. Rigidly attached to the face of conical portion 78 is a bifurcated lever 82, the opposite ends 84 and 86 of which are bent at right angles to the central portion 88 to extend in overlapping relation with the top surface of outer extremities 90 and 92 of valve closure members 62 and 64. At its inner end, shaft 76 is provided with a knurled portion 94 to which is connected a curved lever 96. At its free end, lever 96 is provided with a nylon roller 98 which is adapted for rolling engagement with the top wall 100 of the snap-in cap 20 carried by piston 4. To maintain roller 98 of follower lever 96 in rolling contact with cap 20, there is provided a single acting coiled torsion spring 102, which is connected at one end 104 to lever 96 while its opposite end 106 abuts the inner side wall of dome 2. Follower lever 96 is so formed and dimensioned that roller 98 substantially traverses cap 20 as lever 96 swings upwardly or downwardly about the axis of shaft 76 to follow the reciprocating movement of piston 4.

As will be evident particularly from Fig. 5, when follower lever 96 is swung in a counterclockwise direction responsive to upward movement of piston 4, shaft 76 will rotate in a corresponding direction and cause the end 84 of bifurcated lever 82 to urge the intake valve closure member 62 counterclockwise relative to intake orifice 40 and thereby place the interior of the spring assembly in open communication with the high pressure tank via conduit 26. As air enters the spring assembly through the open intake valve, the relative displacement of dome 2 and piston 4 will progressively increase while follower lever 96 simultaneously rotates in a clockwise direction due to counterclockwise pressure of torsion spring 102 which maintains the roller 98 in constant contact with cap 20. As soon as the predetermined displacement between dome 2 and piston 4 has been achieved, the angular movement of follower lever 96 will have rotated shaft 76 and bifurcated lever arm 82 to a position permitting intake valve closure member 62 to block the flow of air through orifice 40 responsive to pressure of spring 70. As long as the predetermined relative displacement is maintained, no additional air will be admitted through intake orifice 40 or emission through exhaust orifice 42. However, should the relative displacement between dome 2 and piston 4 exceed the predetermined limit, follower lever 96 will resume clockwise movement responsive to spring 102 to maintain roller 98 in continuing contact with cap 20. Thereupon the end 84 of bifurcated lever 82 will urge exhaust valve closure member 64 away from exhaust orifice 42 and permit emission of air from the spring assembly to the low pressure tank via conduit 28 until the predetermined relative displacement is restored, at which time the angular position of lever 82 will permit exhaust valve closure 64 to block orifice 42.

Particular attention is directed to the improved and simplified means of correlating the positions of valve closures 62 and 64 to correspond with the relative vertical position of piston 4 in dome 2. It will be evident that follower lever 96 and roller 98 assure positive uniform rotation of shaft 76 in both a clockwise and a counter-

clockwise direction responsive to vertical movement of piston 4 throughout the latter's normal range of vertical movement. However, in the event of excessive rebound movement of piston 4, roller 98 need not necessarily remain in contact with cap 20. In addition, because each valve closure member 62 and 64 is capable of angular movement substantially in excess of 90° from their closed position, follower arm 96 will tolerate excessive compression movement of piston 4 without affecting normal functioning of the leveling valves through the normal range of movement of piston 4. Because of the mode of effecting synchronous driving engagement between intake and exhaust valves and the piston 4, difficulty of initial installation of the air spring assembly is minimal. Thus, the follower arm 96, shaft 76 and valve housing 50 may be installed as a unit in dome 2 prior to assembly of piston 4 and diaphragm 8. After the spring is completely assembled, valve body 30 is then disposed over the open outer face of housing 50 and secured thereto by means of machine bolts 108 which extend through arcuate slots 110 in valve body 30 and engage the valve housing 50. Since arcuate slots 110 permit limited angular movement of valve body 30, it will be evident that precise adjustment of the desired standing height of a vehicle may be readily accomplished by slightly loosening bolts 108 and rotating the valve body either clockwise or counterclockwise as the case may be. In addition, should inspection, minor repairs or replacement of valve parts be required, the entire mechanism is not only readily accessible but may be removed and replaced without disturbing the valve housing and follower lever mechanism interiorly of the springs.

From the foregoing it will be seen that the present invention affords all the advantages of a fully external leveling valve while eliminating the danger of damage to exposed operating linkage as is the case with fully external valves. Similarly, the follower lever drive mechanism offers all the advantages of internal leveling valves known heretofore while eliminating the complexity, difficulty of assembly and unreliability usually associated with such mechanisms.

While but one embodiment of the invention has been shown and described, it will be evident that other changes and modifications may be made therein. It is, therefore, to be understood that it is not intended to limit the invention to the embodiment shown, but only by the scope of the claims which follow.

We claim:

1. A valve assembly for controlling flow of fluid into and out of a fluid spring of the piston and cylinder type, said valve assembly comprising a valve housing disposed exteriorly of said cylinder and communicating with the interior thereof, a valve body mounted in said housing, an intake valve and an exhaust valve associated with said body, rotary means arranged in one-way driving engagement with said intake valve and exhaust valve respectively, a lever disposed interiorly of said spring and connected to said rotary member, and means on the free end of said lever effecting follower engagement with said piston whereby movement of the latter in one direction causes said rotary member to open said intake and movement of said piston in the other direction causes said rotary member to open said exhaust valve.

2. A valve assembly for controlling flow of compressible fluid into and out of a fluid spring of the type including two relatively movable rigid members and a flexible body connecting said members, said valve assembly comprising a valve housing disposed exteriorly of one of said members and communicating with the interior of said spring, a valve body mounted in said housing, an intake and an exhaust valve associated with said body, rotary means including intake and exhaust valve engaging portions, a lever disposed interiorly of said spring and connected to said rotary member, and means on the free end of said lever effecting follower engagement with

the other of said members whereby movement of the latter in one direction causes said rotary member to open said intake and movement of said piston in the other direction causes said rotary member to open said exhaust valve.

3. A leveling valve assembly for controlling the flow of compressible fluid into and out of a fluid spring of the piston and cylinder type, said valve assembly comprising a valve housing disposed exteriorly of said cylinder and communicating with the interior thereof, a valve body mounted in said housing, an intake and an exhaust valve associated with said body, rotary means including intake and exhaust valve displacing portions, a lever disposed in said spring and connected to said rotary member, means on the free end of said lever effecting follower engagement with said piston whereby movement of the latter in one direction causes said rotary member to open said intake valve and movement thereof in the other direction causes said rotary member to open said exhaust valve, and resilient means urging said lever in a direction providing yielding engagement with said piston.

4. A leveling valve assembly for controlling the flow of compressible fluid into and out of a fluid spring of the piston and cylinder type, said valve assembly comprising a valve housing disposed exteriorly of said cylinder and communicating with the interior thereof, a valve body mounted in said housing, an intake and an exhaust valve associated with said body, a rotary member engaging said intake and exhaust valves and having portions thereon adapted to displace said valves alternately, a lever disposed in said spring and connected to said rotary member, a roller on the free end of said lever effecting follower engagement with the top of said piston whereby movement of the latter in one direction causes said rotary member to open said intake valve and movement thereof in the other direction causes said rotary member to open said exhaust valve, and resilient means urging said lever in a direction providing yielding engagement of said roller with said piston.

5. A leveling valve assembly for fluid springs of the type including a piston and cylinder, said assembly comprising a valve housing extending through and threadably engaging the wall of said cylinder, a shaft rotatably mounted in said housing, a follower lever connected to said shaft and having its free end abuttingly engaging said piston, resilient means acting on said lever to maintain the free end thereof in yielding engagement with said piston throughout the normal range of movement of the latter, a valve body secured to an exterior face of said valve housing to form a closed cavity therein, said body having an integral portion extending into said cavity, an intake and exhaust valve orifice formed in said last mentioned portion, a pair of valve closures swingably mounted in said housing engageable respectively with said intake and exhaust orifices, resilient means engaging said closures to urge the latter to orifice closing positions, means connected to said shaft and engageable with said closures upon rotation of said shaft to selectively open either said intake or exhaust orifice, and means for rotatably adjusting said valve body relative to said housing to correlate the closed positions of said valves with a predetermined relative displacement of said piston and cylinder.

6. A leveling valve assembly for fluid springs of the type including a piston and cylinder, said assembly com-

prising a valve housing having an elongated neck portion extending through and threadably engaging the wall of said cylinder, a shaft rotatably mounted in said housing, a follower lever connected to said shaft, a roller on the free end of said lever engaging said piston, resilient means acting on said lever to normally maintain said roller in yielding engagement with said piston, a valve body secured to an exterior face of said valve housing to form a closed cavity therein, said body having an integral portion extending into said cavity, a pair of spaced orifices mounted in said last mentioned portion, intake and exhaust ports communicating with said orifices, a pair of valve closures swingably mounted in said housing coaxial with said rotatable shaft and engageable respectively with said intake and exhaust orifices, resilient means engaging said closures to urge the latter in opposite directions to effect closing of said orifices, a bifurcated arm rigidly connected to said shaft and having its opposite ends arranged to angularly displace said closures upon rotation of said shaft in opposite directions to selectively open either said intake or exhaust orifice, and means for effecting angular adjustment of said valve body relative to said housing to correlate the closed positions of said valves with a predetermined relative displacement of said piston and cylinder.

7. A leveling valve assembly for fluid springs of the type including a piston and cylinder, said assembly comprising a valve housing having an elongated neck portion extending through and threadably engaging the wall of said cylinder, a shaft rotatably mounted in said housing, a follower lever connected to said shaft, a roller on the free end of said lever engaging said piston, resilient means acting on said lever to normally maintain said roller in yielding engagement with said piston, a valve body secured to an exterior face of said valve housing to form a closed cavity therein, said body having an integral portion extending into said cavity, a pair of spaced orifices mounted in said last mentioned portion, intake and exhaust ports communicating with said orifices, a pair of valve closures swingably mounted on a valve body supported shaft coaxial with said rotatable shaft and engageable respectively with said intake and exhaust orifices, resilient means engaging said closures to urge the latter in opposite directions to effect closing of said orifices, a bifurcated arm rigidly connected to said shaft and having its opposite ends arranged to angularly displace said closures upon rotation of said shaft in opposite directions to selectively open either said intake or exhaust orifice, and means for effecting angular adjustment of said valve body relative to said housing to correlate the closed positions of said valves with a predetermined relative displacement of said piston and cylinder.

8. The structure defined in claim 6 wherein said valve closures include resilient pads arranged to abut said orifices.

9. The structure defined in claim 6 wherein said resilient means engaging said closures comprising a torsionally biased coil spring having one of each of its free ends abutting said one of each of said closures respectively.
